(57) **CLAIM**

The ornamental design for a pump casing, as shown and described.

DESCRIPTION

FIG. 1 is a front perspective view of a pump casing.

FIG. 2 is a further front perspective view of the pump casing.

FIG. 3 is a front view of the pump casing.

FIG. 4 is a rear view of the pump casing.

FIG. 5 is a left side view of the pump casing.

FIG. 6 is a right side view of the pump casing.

FIG. 7 is a bottom view of the pump casing.

FIG. 8 is a top view of the pump casing.

FIG. 9 is a further front perspective view of the pump casing.

FIG. 10 is a further front perspective view of the pump casing.

FIG. 11 is a rear perspective view of the pump casing.

FIG. 12 is a further rear perspective view of the pump casing; and,

FIG. 13 is a bottom perspective view of the pump casing.
